UNITED STATES PATENT OFFICE.

JAMES A. NORTON, OF ODEBOLT, IOWA, ASSIGNOR OF ONE-HALF TO FRED T. THURBER,
OF STERLING, COLORADO.

PUMP.

1,087,253.

Specification of Letters Patent. Patented Feb. 17, 1914.

Application filed August 27, 1912. Serial No. 717,241.

To all whom it may concern:

Be it known that I, JAMES A. NORTON, a citizen of the United States, residing at Odebolt, county of Sac, and State of Iowa, 5 have invented certain new and useful Improvements in Pumps; and I do declare the following to be a full, clear, and exact description of the invention, such as will enable others skilled in the art to which it applies to make and use the same, reference being had to the accompanying drawings, and to the characters of reference marked thereon, which form a part of this specification.

15 My invention relates to improvements in pumps, my object being to provide a device of this character which, while exceedingly simple in construction, shall have a relatively large pumping capacity for a given 20 amount of power expended.

In my improvement I employ two pistons coöperating in the stand-pipe and moving simultaneously in opposite directions, whereby a double-action pumping operation is obtained.

The two pump pistons are operated by means of rods co-axially arranged, one rod being hollow and the other passing therethrough. These two rods are respectively 30 connected with pitmen, the latter being connected with a rotatable ring at diametrically opposite points, whereby, as the ring is rotated by means of suitable power, the rods are simultaneously moved in opposite 35 directions, giving a corresponding movement to the pistons carried by the said rods. A pulley, which may be connected by means of a belt with any suitable motor, is connected with one of the pitmen, the pitman's 40 wrist-pin connecting the rotary ring and power pulley, the said connection being made beyond the center of the pulley to correspond with the wrist-pin's distance from the center of its ring.

45 Each of the pistons is provided with a check-valve, which opens during the downward movement to allow the water to pass therethrough, and closes during the upward movement, whereby the water is lifted and 50 a partial vacuum produced to cause the water to follow the upwardly moving piston.

Having briefly outlined my improved construction, I will proceed to describe the same in detail, reference being made to the ac-

companying drawing, in which is illustrated 55 an embodiment thereof.

In this drawing: Figure 1 is a side elevation partly in section illustrating my improved pump. Fig. 2 is a view of the upper part of the pump viewed at right angles 60 to Fig. 1, being a view looking in the direction of arrow 2, Fig. 1. Fig. 3 is a view similar to Fig. 1 showing the upper part of the pump, with the pitmen, however, in different relative positions from their positions 65 in Fig. 1. Fig. 4 is a sectional view on a larger scale, showing the two pistons arranged in operative relation with the stand-pipe removed. Fig. 5 is a fragmentary sectional view of the construction illustrating 70 one piston and the lower extremity of the stand-pipe. Fig. 6 is a sectional view on a larger scale, illustrating the two piston rods and showing the manner of joining the sections of which they may be composed. 75

The same reference characters indicate the same parts in all the views.

Let the numeral 5 designate the stand-pipe of the pump, in which are located two pistons 6 and 7. The lower extremity of 80 the stand-pipe is provided with a cap 8 threaded upon the lower extremity of the stand-pipe and carrying a flat check-valve 9 adapted to open inwardly as the lowermost piston rises. The lower extremity 85 of the stand-pipe is also provided with a perforated bulb 10 for screening the water as it passes to the pipe.

The lowermost piston 7 is connected with a rod 12 which passes through the piston 6 90 and thence upwardly through a hollow rod 13 which is connected with the piston 6 by means of short rods 14 arranged in parallel relation, their lower extremities being secured to a relatively thin block 15 centrally 95 arranged in the shell of the piston and formed integral therewith, as illustrated in the drawings,—see Fig. 4. This block 15 is provided with a centrally arranged opening 4 through which the rod 12 passes. The 100 lower extremities of the short rods 14 are connected with a cross bar 16, which, in turn, is connected by a coupling sleeve 17 with the lower extremity of the hollow rod 13. The two rods extend upwardly above 105 the ground, the upper extremity of the hollow rod being rigidly secured to a cross head 41 slidably mounted on guide rods 42, the

upper extremity of the rod 12 being connected with a similar cross head 18 also mounted on the guide rod 42, but located above the cross head 41. The lower extremity of a pitman 19 is provided with a bearing 20 which engages a wrist-pin 21 with which the cross head 41 is equipped. The upper extremity of this pitman is provided with a smaller bearing 22 connected with a wrist-pin 23 formed on a ring 24 circumferentially journaled in a stationary ring 30 rigidly supported on the upper extremities of the guide rods 42. A second pitman 34 is provided at its lower extremity 15 with a bearing 25 connected with a wrist-pin 26 with which the cross head 18 is provided. The upper extremity of the pitman 34 is provided with a bearing 27 connected with a wrist-pin 28 connecting the rotary ring 24 20 and the power pulley 29. The wrist-pin 28 is located diametrically opposite the wrist-pin 23 of the ring 24 and it is connected with the pulley 29 at the same distance from the center of the latter as from the center 25 of motion of the rotary ring.

The ring 24 has its periphery provided with a circumferential groove forming a half-bearing for balls 31 which engage a smaller groove formed in the stationary ring 30, which constitutes a support for the rotary ring. The stationary ring 30 is composed of two parts, which, as illustrated in the drawing, are connected by cap-screws 32 or other suitable fastening devices, where- 30 by they are readily detachable and replaceable whenever occasion may require. It will be understood that in order to place the bearing balls 31 in place it will be necessary to remove the upper member of the 35 stationary ring 30. After the balls are in place, the ring member may be put in position.

In order to properly balance the structure and distribute the power on opposite 40 sides of the axis of the piston rods, the pitmen 19 and 34 are connected with the rotary ring 24 on opposite sides of the latter. The power pulley 29 also serves as a fly-wheel in the operation of the pump. As 45 illustrated in Figs. 2 and 3 of the drawing, the power pulley 29 is provided with a crank 33 provided with a handle 35 to permit manual operation of the pump if desired. Each of the pistons 6 and 7 is V- 50 shaped at its upper extremity, as shown at 36, and is provided with check-valve members 37 arranged to open inwardly toward the axial center of the pump rods during the downward movement of the piston. This 55 opening feature is illustrated in Figs. 1 and 5 of the drawing.

Where the well, or shaft, is of considerable depth, the pump rods 12 and 13 will be formed in sections and suitably connected 60 together. In Figs. 6 I have illustrated one

way of connecting these sections. Let the letter A designate two sections of the hollow rod 13. These sections may be connected together by a sleeve B, the latter being internally threaded at its extremities to receive the corresponding exteriorly threaded portions of the sections A. Again, the sections C of the rod 12 have a threaded connection with a short sleeve D, the latter being interiorly threaded to receive the exteriorly 70 threaded portions of the rod sections. 75

From the foregoing description, the use and operation of my improved pump will be readily understood. When the pump is in operation, the two pistons 6 and 7 move simultaneously in opposite directions, each of the pistons moving alternately upwardly and downwardly. Referring to Fig. 1, it will be observed that the two pistons 6 and 7 are respectively at the limit of their upward and downward movement since their pitmen 19 and 34 are directly in alinement, hence it must be assumed that the stand-pipe 5 is filled with water between the two pistons, and that the water also fills the stand-pipe above the piston 6 of the discharge nozzle 39. It must also be assumed that during the upward movement of the piston 6 the water above the piston in the stand-pipe has been carried upwardly, causing a continuous 90 discharge from the nozzle 39 into the chute, or trough, 40. Now as the rotary ring 24 continues its movement from a position shown in Fig. 1, the piston 6 will descend and the piston 7 ascend in the stand-pipe. 95 As the piston 6 moves downwardly, its check-valve members 37 will open, (see Fig. 5) and allow the water between the two pistons to pass upwardly therethrough, this water being lifted during its passage through the piston 6 by the rising piston 7. These check-valve members 37 are, of course, closed in response to the pressure of the water during the piston's rising movement. Hence, as the piston 7 is lifting the water in the 100 stand-pipe and this water is allowed to pass freely to the piston 6, the water will be lifted in the stand-pipe and keep up a constant discharge or flow of water through the nozzle 39. From this it will be understood that 105 when the pump is in operation one of the pistons is practically always on the upward movement, since no appreciable time elapses during the stopping of the piston's movement in one direction and the beginning of 110 its movement in the opposite direction, and for this reason there will be a continuous flow of water through the discharge nozzle 39 during the operation of the pump, giving practically twice the flow that could be obtained if a single piston only were employed.

Again, very little power is required to operate the pump, since during the upward movement of the wrist-pin connected with one pitman, the diametrically located wrist- 115 120 125 130

pin on the ring 24 is making its downward movement and the weight of the parts connected therewith is advantageously applied to balance the upwardly moving parts connected with the first named wrist-pin. It will thus be observed that the construction is exceedingly well-balanced, and, therefore, easily and economically operated.

Having thus described my invention, what I claim is:

1. In a pump, the combination of a cylinder, pistons located therein and operably equipped with check-valves, the pistons being in axial alinement and co-operatively arranged, rods respectively connected with the pistons and co-axially alined, cross heads with which the rods are respectively connected, one cross head having an opening through which the rod of the other cross head passes, guides for the cross heads, a ring-bearing rigidly secured to the guides, a

ring rotatably mounted in the said bearing, pitmen connected with the rotary ring at diametrically opposite points, the said pitmen being respectively connected with the cross heads, substantially as described.

2. In a pump the combination with a pipe of two coöperating pistons located therein and equipped with check valves to allow the water to flow therethrough in one direction, a ring bearing rigidly secured at one end of the pipe, a ring rotatably mounted in said bearing and connected in operative relation with the pistons, whereby when the ring is rotated the said pistons will be moved simultaneously in opposite directions.

In testimony whereof I affix my signature in presence of two witnesses.

JAMES A. NORTON.
